CLAIM

The ornamental design for a ceiling fan light globe, as shown and described.

DESCRIPTION

FIG. 1 is a top perspective view of a ceiling fan light globe of a ceiling fan according to my invention;

FIG. 2 is a bottom perspective view of the light globe of FIG. 1;

FIG. 3 is a right side elevational view of the light globe of FIG. 1; with front, left and back side views being identical thereto.

FIG. 4 is a top elevational view of the light globe of FIG. 1; and,

FIG. 5 is a bottom elevational view of the light globe of FIG. 1.

Portions of the ceiling fan light globe or ceiling fan shown in broken lines form no part of the claimed design.
